UNITED STATES PATENT OFFICE.

EDMUND M. SCHOLLENBERGER, OF CHICAGO, ILLINOIS, ASSIGNOR OF ONE-HALF TO
LEE A. STAHL, OF CHICAGO, ILLINOIS.

ATTACHMENT FOR TELEPHONE-TRANSMITTERS.

1,072,513.

Specification of Letters Patent.

Patented Sept. 9, 1913.

Application filed September 12, 1912. Serial No. 719,958.

To all whom it may concern:

Be it known that I, EDMUND M. SCHOLLENBERGER, a citizen of the United States, residing at Chicago, in the county of Cook and the State of Illinois, have invented certain new and useful Improvements in Attachments for Telephone-Transmitters, of which the following is a specification.

This invention relates to improvements in attachments for transmitters particularly adapted, though not necessarily limited in its use in connection with telephone transmitters, and one of the objects of the invention is to provide an improved attachment of this class whereby a clear and distinct sound will be delivered to the transmitter, while at the same time the message when spoken into the attachment, in the ordinary or a lower tone, cannot be heard by another person in the same room.

A further object is to provide an improved device of this class which will be simple, durable, cheap and light in construction, readily attached and detached and which will be effective and efficient in operation.

To the attainment of these ends and the accomplishment of other new and useful objects as will appear, the invention consists in the features of novelty in substantially the construction, combination and arrangement of the several parts hereinafter more fully described and claimed and shown in the accompanying drawing illustrating the invention and in which,

Figure 1 is a perspective view of an improved attachment of this class constructed in accordance with the principles of this invention and showing the same attached to a telephone transmitter. Fig. 2 is a longitudinal, sectional view of the attachment.

Referring more particularly to the drawing, the attachment may be constructed of any desired size and material and may be of any desirable configuration, and constructed in any suitable manner. In the present exemplification of this invention the attachment is shown in the form of a hollow body which is of sectional construction and comprises two sections 10, 11 each

of which is in the form of a hollow cone and at the apex of the respective cones 10, 11, openings 12, 13 are formed. At the base of the cone 10 a flange 14 is formed and this flange is arranged at an angle to the remaining portion of the cone and may be of any desired width. A similar flange 15 is formed at the base of the other cone section 11 and is adapted to receive the flange 14 of the section 10. The two sections 10 and 11 thus formed may be detachably secured together in any desired or suitable manner so that they can be separated to permit the attachment to be secured to the transmitter and also for cleaning. A suitable means for thus securing the sections together comprises a bayonet slot being carried by one of the sections while the co-operating projection or lug is carried by the other section.

A mouth piece 17 of any desired size and configuration is formed on the section 11 and around the opening 13. When the sections 10 and 11 are secured together, the openings 12 and 13 will be arranged opposite to and spaced from each other and the body will increase in internal diameter from the apexes of the cones toward the longitudinal center of the body. Thus it will be seen that the sections 10 and 11 of the body may be readily separated and connected and when connected the joint formed between the sections will be a close fit so as to confine the sound within the body. In order to connect the attachment to the transmitter the sections 10 and 11 are separated and the mouth piece 18 of the transmitter of the instrument designated generally by the reference numeral 19 is removed. After being removed the mouth piece is passed through the opening 12 of the section 10 from the inside of the section and the opening 12 is of a size less than the receiving end of the mouth piece so that the mouth piece will not pass entirely through the opening as shown in Fig. 2. The mouth piece 18 is then again secured to the transmitter in the ordinary and usual manner. In order to support the section 10 projections 20 in the form of arms or feet are provided on the section 10 and are adapted to rest against the face 100

plate of the transmitter 21. These arms or feet are of such a length that when the mouth piece 18 is seated with respect to the transmitter, they will be forced against the face of the transmitter owing to the fact that the enlarged end of the mouth piece will bind in the opening 12 and will draw the feet against the face plate, thereby holding the section 10 rigidly in position. If 10 desired a suitable packing in the form of a gasket constructed of felt, rubber or the like may be provided to surround the mouth piece 18 adjacent to the opening 12 and to extend into the opening so as to form 15 a tight joint. If desired a suitable fastening device 22 such as a screw or the like may be provided which passes through the wall of the section 10 and binds against the outer face of the mouth piece 18. When 20 the section 10 is thus secured in position the section 11 may be readily attached to the section 10 by properly positioning with respect to the section 10 and then giving it a partial rotation to lock the bayonet joint. 25 The body being of a light construction will be readily supported and held in position by the mouth piece 18 and the arms or feet 20, and the mouth piece 17 will be in a proper position for the user.

30 With this improved construction the user of the telephone by placing his mouth close to the mouth piece 17 can speak into the attachment and the sound will be transmitted to the transmitter through the mouth piece 35 18. Inasmuch as the conversation or the sound of the voice is confined within the attachment or body, it will be directed to the mouth piece 18 of the transmitter and a clear tone will be the result. With this 40 improved construction it is possible to carry on a conversation in an ordinary tone which will not be heard by another occupant of the same room. It is also possible to speak into the telephone with this attachment in 45 a much lower tone than has heretofore been possible and at the same time be clearly heard by the person at the other end of the line.

While in the present exemplification of 50 this invention only one shape or form of the device is illustrated, it is to be understood that many changes may be made in the sizes, shapes and proportions of the parts without departing from the spirit of the invention. 55 This attachment also serves to correct a fault of a number of users of the telephone, that is, it prevents persons who are accustomed to talking very loud, from placing the mouth too close to the transmitter there- 60 by obviating the resulting objections from such a manner of using the telephone.

It will be noted that the opening 13 is of a length greater than its width and that the annular flange 17 which surrounds this open-

ing is of a similar shape so as to conform 65 to the mouth of the user.

What is claimed as new is:—

1. A device of the class described, comprising a hollow casing having opposed reduced portions, each of which portions is 70 provided with an opening therethrough, and said casing being formed in sections secured together for separation, the mouth piece of the transmitter passing through one of the openings from the inside of the casing, the 75 last said opening being of a size less than the receiving end of the transmitter whereby the transmitter will fit snugly into the opening for supporting the casing, and a shield encompassing the other opening outside of 80 and projecting a short distance beyond the casing.

2. A device of the class described, comprising a hollow casing having opposed reduced portions, each of which portions is 85 provided with an opening therethrough and said casing being formed of sections secured together for separation, the mouth piece of the transmitter passing through one of the openings from the inside of the casing, the 90 last said opening being of a size less than the receiving end of the mouth piece, and means connected with and projecting from the casing and adapted to contact with a portion of the instrument and operating 95 to cause the mouth piece to be wedged into said opening, when the mouth piece is fastened to the transmitter.

3. The combination of a hollow body comprising separable sections having openings therethrough, a transmitter mouth piece passing through one of the openings from the inside of the section and with the receiving end of the mouth piece inside the 100 section, means engaging the said body and 105 a portion of the instrument and coöoperating with the said mouth piece for holding the body in position, and an annular flange surrounding the other opening.

4. The combination of a hollow body comprising separable sections having openings therethrough, a transmitter mouth piece passing through one of the openings from the inside of the section and with the receiving end of the mouth piece inside the 115 section, means engaging the said body and a portion of the instrument and coöoperating with the said mouth piece for holding the body in position, an annular flange surrounding the other opening, and additional 120 means for holding the attachment in place.

5. The combination of a hollow body comprising separable sections having openings therethrough, a transmitter mouth piece passing through one of the openings from the inside of the section and with the receiving end of the mouth piece inside the 125 section, means engaging the said body and

a portion of the instrument and coöperating with the said mouth piece for holding the body in position, an annular flange surrounding the other opening, and a fastening 5 screw for assisting in holding the parts in position.

In testimony whereof I have signed my

name to this specification, in the presence of two subscribing witnesses, on this 4th day of September A. D. 1912.

EDMUND M. SCHOLLENBERGER.
